UNITED STATES PATENT OFFICE.

JOZEF SEPNISWICZ, OF NEWARK, NEW JERSEY.

AEROPLANE.

1,322,632.

Specification of Letters Patent. Patented Nov. 25, 1919.

Application filed August 5, 1918. Serial No. 248,359.

To all whom it may concern:

Be it known that I, JOZEF SEPNISWICZ, a citizen of Poland, residing at Newark, in the county of Essex and State of New Jersey, have invented certain new and useful 5 Improvements in Aeroplanes, of which the following is a specification.

This invention relates to aeronautics, and more especially to propelled flying machines; 10 and the object of the same is to greatly simplify and improve a machine of this type without losing sight of the possibilities of those now in use.

Primarily, the invention consists of employing a flat lifting plane of deltoid shape moving along its major axis with its sharpest portion forward.

The propelling means here shown and described comprises a pair of engines and propellers, one under each end of the major 20 axis.

Another feature of the invention is a second plane approximating the shape of the first and subjacent thereto.

25 Another feature of the invention lies in fastening the planes in strict parallelism with each other, and propelling them through the air with their front ends or points higher than their rear ends, so that 30 their bodies incline downwardly and rearwardly. The peculiar shape of the lifting plane, and possibly also the shape of the other plane, avoids the necessity for lateral wings, either fixed or movable.

35 Another feature of the invention is the flexibility of the front end of the lifting plane, whereby it may be adjusted manually to cause the machine to ascend or descend. This avoids the necessity for a tail.

40 Other features and details are brought out in the following specification and claim, and reference is made to the drawings wherein:

Figure 1 is a plan view of the lifting 45 plane.

Fig. 2 is a side elevation of this machine complete.

Fig. 3 is a horizontal section taken just 50 beneath the lifting plane and showing the lower plane and the propelling mechanisms.

I will say at starting that I have shown only so much of the machine as is necessary for a clear understanding of the invention, and much of the illustration is merely dia- 55 grammatic. From the success I have had

with a working model of this invention, I am inclined to believe that its most important feature lies in the specific shape and disposition of the lifting plane, and therefore I will describe the same minutely. The 60 contour of the upper or lifting plane, as shown in the drawings, follows the outline of two isosceles triangles with their bases together. These triangles are of different areas, but their bases are coincident. The 65 figure resulting is a kite-shaped trapezium or more specifically a symmetrical trapezium, defined by one authority (Funk & Wagnall's Dictionary, 1917) as a "deltoid" and so called hereinafter; and in the use of a supporting 70 or lifting plane of this shape, I consider it desirable if not absolutely essential that the sharpest point shall move forward. The plane as a whole is designated in the drawings by the numeral 1, its forward point is 2, 75 its rearward point is 3, its major axis 4 connects these points and is coincident with the line of travel as indicated by the numeral 5 in Fig. 1, and its minor axis 6 is transverse to the major axis and disposed substantially 80 three-quarters of the distance from the front or forward point 2 back to the rearward point 3. Therefore the greatest width of the plane is to the rear of its longitudinal center; and while I do not wish to be limited 85 at all in this respect, I would suggest that the width should be about half its length. The structure of the plane itself is immaterial. Preferably it will be composed of suitable fabric stretched flat in a single 90 plane upon a frame of light but strong structure and with appropriate bars and braces not necessary to elaborate. At about one-third of the distance from the front 2 to the rear 3, a frame bar 7 is shown in dotted lines 95 in Fig. 1, and the front end of the major or larger portion of the plane, forward of this bar and indicated broadly by the numeral 8, may flex vertically as shown by the dotted lines in Fig. 2. Suitable mechanism preferably is employed for raising and lowering this front end so as to carry it strictly out of the plane of the remainder of the structure, whereby the aviator may cause his machine 100 to ascend or descend at will.

The second plane, herein called a subjacent plane, is indicated broadly by the numeral 11. Its shape is shown in Fig. 3 as being approximately that of the upper or lifting plane, except that it does not extend 105 110

beneath the flexible tip 8, and it is herein illustrated as disposed beneath said lifting plane and entirely parallel therewith. It also is flat and may be made in any suitable manner, and uprights 12 connect the two planes at appropriate points while still leaving the front end 8 of the lifting plane free to flex. Landing wheels 13 and 14 are carried in appropriate hangers depending from the subjacent plane, there being a single forward wheel 13 and a pair of rearward wheels 14; but it is important to note that the hangers are of such length that both planes are canted upward at their front ends so that they incline downward and rearward to a strictly horizontal line. This inclination of the planes is permanent. It exists when the machine rests upon level ground, and it is an inclination which is nicely calculated to be such that when the machine is progressing forward at average speed it will be sustained in a horizontal path. I may also provide a single forward float 15 and two rearward or lateral floats 16 to sustain the machine in case it should drop upon the water. I prefer to employ a front engine and its propeller 17 and a rear engine and its propeller 18, these rotating simultaneously and in opposite directions, but the blades of the propellers are pitched so that they work in conjunction with each other. The weight of these machines should be disposed forward and rearward of the longitudinal center of the sustaining plane, so that ordinarily the machine will not drop down at either end when the aviator is in place. His seat should be midway between the machines, but I have not illustrated the seat or other details.

While it is true that what I may believe as to the efficacy of a lifting plane of the shape shown and described is mostly theoretic, certain propositions are more or less self-evident. A plane which comes to a point at the front, rather than one having a straight and long front edge, will cut the air with greater ease. A plane whose general area lies fore and aft or along the line of progress rather than transverse thereto will possess greater stability longitudinally and less stability transversely: the former I take advantage of, and the latter I guard against by causing the edges of the main or forward portion of the plane to diverge from its point 2 to the rear to the extremities of the minor axis 6, and then converge quickly to the rearward point 3. An air craft plane which has no lateral wing tips, rigid or flexible, is considered liable to tilt: this I guard against by disposing the weight of the engines and the aviator along and beneath the major axis of the lifting plane, so that when tilting

does occur its weight is swung aside and its tendency to return to the lower point overcomes the tilting. A plane which is long along the line of movement rather than wide across it may readily be employed as a horizontal rudder by rendering a portion of it flexible; as the widest and rearward portion of my main plane is used for sustaining the machine, I render the front end flexible and carry this flexibility back to a point where I find it sufficient to cause the rise and fall of the machine. Whatever advantages arise from the use of a deltoid upper plane, may result also from the use of a lower plane of approximately the same shape; and I will here say that I do not wish to be confined to the use of a plurality of planes, nor to the use of two planes only.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claim.

Having thus fully described my invention, what I claim as new and desire to secure by Letters Patent, is:—

In an aeroplane of the character described, the combination of an upper plane which is deltoidal in shape with its sharpest point forward, said plane having a transverse frame bar in rear of the sharp point to allow this point to be flexed, a subjacent plane spaced below said upper plane and being substantially similar in shape thereto, uprights connecting the planes together, a motor and propeller mounted upon the subjacent plane in line with the major axis thereof and contiguous to its forward and rear points, whereby the area of the lower plane contiguous to the points extending in alignment with the minor axis thereof will be unobstructed, landing wheels having brackets of different lengths connected to the lower plane, thus causing both planes to be held in inclined position with respect to the horizontal, whereby when the motors are started, the aeroplane will be lifted without the flexing of said first mentioned point, while the deltoidal shape of said planes will reduce air resistance thereagainst and will also act as a stabilizer for holding the plane from tilting sidewise, as and for the purposes set forth.

In testimony whereof I affix my signature in presence of two witnesses.

JOZEF SEPNISWICZ.
